FLUID PRESSURE OPERATED APPARATUS

Kaleb Emil Evrell, Eskilstuna, Sweden, assignor to
 Aktiebolaget Bolinder-Munktell, Eskilstuna,
 Sweden, a corporation of Sweden

Application September 22, 1937, Serial No. 165,209
 In Sweden October 3, 1936

3 Claims. (CL. 143—125)

The present invention relates to apparatus operated by a fluid under pressure, such as compressed air or liquid, delivered from a common source of supply and adapted to actuate a plurality of servo-motors arranged to transmit power to different places of consumption. In particular, the invention relates to a controlling device for such apparatus.

The primary object of the invention is the provision of means to ensure that one or more of the servo-motors always can be supplied with sufficient working fluid at the desired pressure, even if the pressure of the fluid acting upon other servo-motors should be temporarily decreased, for instance on account of a reduced resistance exerted upon the last-named servo-motors. Another object of the invention is to arrange the servo-motors in a manner such as to be automatically actuated in succession according to a predetermined order.

For a better understanding of the nature of the invention together with further objects and advantageous details and combinations of parts, and the manner in which it is carried into effect, reference may be had to the accompanying drawings forming a part of this specification and the following description thereof. Two embodiments of the invention are illustrated in the drawings, the first embodiment showing the invention as applied to an actuating device for log carriages and the second embodiment showing the invention as applied to a controlling apparatus for pressure diecasting machines.

In the drawings:

Figure 1 shows a rear elevation of a log carriage provided with a fluid pressure operated device in accordance with the invention;

Figure 2 is a side elevation of the log carriage shown in Figure 1;

Figure 3 is a top view of the log carriage;

Figure 4 shows in a more diagrammatic manner a section of the controlling device employed in the log carriage;

Figure 5 is a detail of Figure 4 on a larger scale;

Figure 6 is a section taken on the line VI—VI of Figure 4 on a larger scale.

Referring to Figs. 1-3, the reference numerals 1 and 2 designate two haulage chains by means of which the log carriage is moved and which are travelling in opposite directions, as indicated by the arrows 1' and 2' respectively. The chains 1 and 2 are in permanent mesh with chain wheels 3 and 4, respectively, mounted in the carriage. Reference numerals 5 and 6 designate

respectively can be locked. The braking mechanism forms no part of this invention and is not shown in detail in the drawings. If the chain wheel 3 is locked the log carriage follows the chain 1 meshing with the said wheel in the direction of the arrow 1' towards the saw frame. If the chain wheel 4 is locked and the chain wheel 3 released the carriage will move in the opposite direction. For the purpose of holding a log on the carriage there are provided dogs or jaws 7 and 8 pivotally secured to a jaw head 9. By means of a hand wheel 10 the gripping device 7-8 may be turned, independently of the pressure actuated mechanism to be described hereinbelow, about an axis parallel to the direction of movement of the carriage, and by means of a lever 11 the gripping device may be turned about a shaft 12 so that it will be possible to lower the jaws down to the log carrier 13, in order that they shall not hinder a log from being rolled upon the carriage.

The log carriage is fitted with servo-operated devices for clamping or gripping the log and for side shifting and turning the same about its own axis. In the embodiment illustrated, the power necessary for supplying the servo-motors with fluid under pressure is derived from the haulage chains 1 and 2 by means of a transmission device in the form of a differential gear the primary or driving wheels of which are the chain wheels 3 and 4. The transmission device is preferably in the form described in my co-pending patent application Serial No. 123,709, filed February 2, 1937, or of any other suitable type. By means of the transmission gear which is enclosed by a casing 17, a pump 19 is driven so as to produce a hydraulic pressure.

As will be best seen from Fig. 4, the pump 19 is supplied with liquid from a liquid container 20 through a conduit 21. The container 20 is closed by a small cover 22 provided with an opening 23. By means of a conduit 24 and a flexible pipe 25 the discharge side of the pump 19 is connected to a control valve 26 formed as a four-way valve and manually operable by means of a handle 27. The flexible pipe 28 connects the valve 26 with the container 20.

The jaws 7 and 8 are linked to a cross-piece 29 connected to a rod 30 which at its other end forms a piston 31 adapted to slide in a cylinder 32 slidably mounted on the shaft 12. The spaces above and below the piston 31 are connected with the valve 26 by means of the conduits 33 and 34. A by-pass conduit 35 provided with a pressure relief valve 36 connects the conduit 24 directly

to the container 20. The pressure relief valve 36 is held in closed position by a helical spring 37, the tension of which is such that the valve will be opened if the pressure in the conduit 24 rises above the highest permissible value.

Mounted in the container 20 is a control valve 38 having an inlet passage 39 and an outlet passage 40 (see Fig. 5). By means of a helical spring 41, the one end of which rests against a 10 ring 42 screwed into the casing of the valve 38 and provided with an aperture 43, a piston 44 is forced into the inlet passage 39 and thereby prevents flow of liquid from the passage 39 to the passage 40. The inlet passage 39 is connected to the pipe 25 by means of a conduit 45. A flexible pipe 46 connects the outlet passage 40 to a four-way valve 47 operable by a handle 48 and to another control valve 49 which is designed in the same manner as the control valve 38. By means of conduits 50 and 51 the four-way valve 47 is connected to a stationary cylinder 52. A piston 53 adapted to slide in the cylinder 52 is connected to the cylinder 32 by a piston rod 54. Upon movement of the piston 53 the cylinder 32 together with the jaw head 9 and the jaws 7, 8 will be shifted sideways in the one or the other direction.

The outlet passage 55 of the control valve 49 is connected by means of a conduit 56 to a four-way valve 57 which can be manually operated by a handle 58. By means of two conduits 59 and 60 the four-way valve 57 is connected to a cylinder 61 rigidly connected to the cylinder 32 and provided with a stationary piston 62 and a rotary piston 63 mounted on a shaft 64 which at its outer end carries a pinion 65 (see Fig. 6). By the pistons 62 and 63 the cylinder 61 is divided into two compartments 66 and 67 which may be brought into communication with the four-way valve 57 by means of the conduits 59 and 60. The jaw head 9 is rotatably mounted on an axial elongation 68 of the cylinder 32 and formed into a gear wheel 69 adapted to mesh with the pinion 65. It will thus be seen that upon rotation of the shaft 64 the jaw head together with the jaws and the log 70 clamped between them will be turned around the axis of the piston rod 30. By means of conduits 71 and 72 the four-way valves 47 and 57 are connected to each other, and by means of a flexible return pipe 73 the said valves are connected to the liquid container 20. The space behind the piston of the control valve 49 is connected to the pipe 73 by means of a conduit 74.

55 The apparatus described operates in the following manner.

If a log is to be clamped between the jaws 7 and 8 the four-way valve 26 is brought into the position shown in Fig. 4. Liquid under pressure 60 is then supplied from the container 20 through the conduit 21, the pump 19, the conduits 24 and 25, the valve 26 and the conduit 33 to the upper space of the cylinder 32. The piston 31 will then be moved downwards, as viewed in Fig. 4, so that 65 the jaws will be brought into engagement with the log 70. Liquid which is contained in the cylinder 32 below the piston 31 will thereby be returned to the container 20 through the conduit 34, the valve 26 and the return pipe 28. It is assumed that the gripping device is to be shifted sideways from the right to the left, and for this purpose the four-way valve 47 is adjusted into the position shown in Fig. 4, in which the conduit 70 75 46 is in communication with the space of

the cylinder 52 on the right-hand side of the piston 53.

During the time in which the jaws 7 and 8 are moving towards the log 70 the resistance acting against the movement of the piston 31 is comparatively small and, as a result thereof, the pressure of the liquid in the conduits 24, 25 and 33 will be considerably lower than the pressure at which the piston 44 of the control valve 38 can be moved inwardly so as to connect the conduits 45 and 46. Preferably, the spring 41 counteracting such movement of the piston 44 has an initial tension of the order of 80% of the maximum pressure at which the non-return valve 36 opens the conduit 35. During the movement of the jaws 7, 8 towards the log, the pressure in the conduit 25 is considerably lower than 80% of the maximum pressure, with the result that the control valve 38 will prevent liquid from flowing into the pipe 46. As soon, however, as the jaws are firmly pressed against the log, the pressure of the liquid rises above 80% of the maximum pressure and the piston 44 of the control valve will be moved inwardly against the resistance of the spring 41 so that liquid can flow from the conduit 45 to the conduit 46 and through the valve 47 into the conduit 51 and the right-hand side of the cylinder 52. The gripping device will then be moved towards the left. Liquid contained in the left-hand side of the cylinder 52 is returned to the container 20 through the pipes 50, 72 and 73.

The movement of the gripping device in lateral direction requires as a rule only a comparatively small power. Were it not for the control valve 38 a reduction in the pressure of the liquid caused by a rapid movement of the piston 53 would be transmitted through the conduit 25 to the upper space of the cylinder 32 so that the pressure at which the jaws are forced towards the log might be decreased to such an extent that the log would no longer be held with the necessary power. The control valve 38, however, prevents a reduction in the pressure acting upon the piston 31 independently of the pressure prevailing in the conduit 46. Should the last-named pressure fall below 80% of the maximum pressure, the valve 38 will shut off the connection between the conduits 45 and 46 so that the reduction of the pressure in the conduit 46 will have no influence upon the pressure in the conduit 25 which pressure will thus always be maintained between 80% and 100% of the maximum pressure.

If the gripping device is to be moved in the opposite direction, the body of the four-way valve 47 is turned by means of the handle 48 through an angle of 90°. The pressure conduit 46 will then communicate through the valve with the conduit 50, while the conduit 51 will be connected to the return pipes 72 and 73. In the intermediate position of the handle 48, the cylinder 52 is entirely shut off from the conduit 46.

In order to actuate the turning device, and handle 58 of the four-way valve 57 is turned through an angle of 45° from the position shown in the one or the other direction, as the case may be. Pressure liquid will, however, not flow through the conduit 56 to the valve 57 unless the following two conditions are fulfilled. Firstly, the pressure in the conduit 25 must be so high that the control valve 38 opens the connection between the conduits 45 and 46; this condition prevails if the jaws 7 and 8 have been brought into engagement with the log 70. Secondly, the pressure in the conduit 46 must be so high that the

5 piston of the control valve 49 opens the connection between the conduits 46 and 58; this second condition is fulfilled if the valve 47 is in its intermediate position in which the conduit 46 is entirely shut off from the cylinder 52, or if the piston 53 has reached either of its end positions, or if the resistance exerted against the movement of the piston 53 is strong enough to produce a counter-pressure which can move the piston of 10 the control valve 49 inwardly against the resistance of the spring of the said valve. If the valve 57 is so adjusted that it connects the conduits 56 and 59 to each other, the space 66 of the cylinder 61 will be filled with liquid under pressure and 15 the piston 63 will be turned in a clockwise direction. This turning movement is transmitted to the jaw head 8 by means of the shaft 64 and the gear wheels 65 and 66. In this position of the four-way valve 57, the space 67 of the cylinder 61 20 will be brought, through the pipe 60, into communication with the return pipes 71 and 73. If the valve 57 is adjusted such that the pressure conduit 58 is brought into communication with the conduit 60, the space 67 will be filled with 25 liquid under pressure and the jaw head will be turned in the opposite direction.

To release the jaws from the log, the body of the four-way valve 26 is turned through a right angle so that the liquid under pressure will flow 30 from the conduit 25 to the conduit 34 and move the piston 31 upwardly whereby the jaws will be turned out of engagement with the log. In the intermediate position of the valve 26 the gripping device is put out of operation.

35 By means of the conduit 74, liquid which leaks along the piston of the control valve 49 can flow to the return pipe 73.

Many changes and variations in the specific construction of apparatus for carrying the invention into effect will occur to those skilled in the art and it is to be understood that the scope of the invention is not limited to the embodiments hereinbefore illustrated and described by way of example, but is to be considered as including all 40 forms of apparatus falling within the scope of the appended claims when they are construed as broadly as is consistent with the state of the prior art.

What I claim is:

50 1. In a log carriage for saw mills, a gripping

device for holding a log during the sawing operation, a first servo-motor for actuating said gripping device, means for side shifting said gripping device, a second servo-motor for actuating said shifting means, an impeller for delivering fluid under pressure, a first conduit for connecting said impeller with said first servo-motor, a second conduit for connecting said impeller with said second servo-motor, and a control valve in said second conduit, said control valve being adapted 10 to be opened upon increase in the pressure of said fluid above the pressure required for actuating said first servo-motor.

2. In a log carriage for saw mills, a gripping device for holding a log during the sawing operation, a first servo-motor for actuating said gripping device, means for turning said gripping device, a second servo-motor for actuating said turning means, an impeller for delivering fluid under pressure, a first conduit for connecting 15 said impeller with said first servo-motor, a second conduit for connecting said impeller with said second servo-motor, and a control valve in said second conduit, said control valve being adapted to be opened upon increase in the pressure of 20 said fluid above the pressure required for actuating said first servo-motor.

3. In a log carriage for saw mills, a gripping device for holding a log during the sawing operation, a first servo-motor for actuating said gripping device, means for side shifting said gripping device, a second servo-motor for actuating said shifting means, means for turning said gripping device, a third servo-motor for actuating said turning device, an impeller for delivering fluid 30 under pressure, a first conduit for connecting said impeller with said first servo-motor, a second conduit for connecting said impeller with said second servo-motor, a third conduit for connecting said impeller with said third servo-motor, 40 a first control valve in said second conduit, said control valve being adapted to be opened upon increase in the pressure of said fluid above the pressure required for actuating said first servo-motor, and a second control valve in said third 45 conduit, said second control valve being adapted to be opened upon increase in the pressure required for actuating said second servo-motor.

KALEB EMIL EVRELL. 50
